UNITED STATES PATENT OFFICE.

EDWIN J. CONLEY, OF NEW YORK, AND EDWARD J. WHALEN, OF HOWARD BEACH, NEW YORK, ASSIGNEES TO THE CONLEY FOIL COMPANY, OF NEW YORK, N. Y., A CORPORATION OF NEW YORK.

RECEPTACLE-SEALING MACHINE.

Application filed May 29, 1922. Serial No. 564,554.

To all whom it may concern:

Be it known that we, EDWIN J. CONLEY, a citizen of the United States, and a resident of New York, county and State of New York, and EDWARD J. WHALEN, a citizen of the United States, a resident of Howard Beach, in the county of Queens and State of New York, have invented a certain new and useful Receptacle-Sealing Machine, of which the following is a specification.

This invention relates to a receptacle sealing machine, and more particularly to a machine for fusing tin foil to the sides of a tin receptacle.

The general principles of sealing tin foil to a corresponding metallic material have been disclosed in the patent to Edwin J. Conley, 1,398,840, and this invention is particularly concerned with a machine for accomplishing a similar object, on packages of various characters, by the use of sealing irons enclosed in rollers between which the package is made to pass. While the invention may exist in various embodiments, for the sake of a specific description the following embodiment will be described in connection with the accompanying drawings which form part of the specification.

In said drawings,

Fig. 1 represents a side view of the machine with the rollers separated;

Fig. 2 represents a section of the machine and rollers at right angles to Fig. 1 through the axes of the rollers;

Fig. 3 represents a detailed view of a modified form of roller, and

Fig. 4 represents certain electrical connections which may be made for properly operating a rheostat used in conjunction with the machine.

In said drawings there are shown standards 1 and 2, each provided with grooves such as 3 and 4 to accommodate upper and lower blocks 5, 6 and 7, respectively (the block for roller 12 not being visible in Fig. 2 because of the gears). Within these slideable blocks are positioned rollers 9, 10, 11, and 12, respectively, and these rollers are mounted to rotate on roller bearings as clearly illustrated in the drawings, said roller bearings being denoted generally by the numeral 13. The roller bearings are provided with suitable channels or grooves 14 cut therein for lubrication purposes, and they

are set within corresponding sockets 15 in the rollers. The bearings travel within stationary annular members or races 16 which are cut away as shown in Fig. 1 so that the rollers may be brought into contact if desired. The roller bearings are supported within their sockets by the side walls thereof as shown in Fig. 1, and can only be removed by longitudinal sliding displacement. Inside of the rollers are mounted electrical heating irons such as irons 17, 18, and 19, and these may be spaced from the rollers about 1/64". The irons are connected to a rheostat 20 by suitable electric wires as shown, the specific manner of arranging the electrical connections being described later.

At the side of the standards are provided suitable slots such as 21 and 22 adapted to receive locking bolts 23 for the purpose of engaging and holding plates such as 24, in which are mounted gears such as 25 and 26 meshing with gears such as 27 and 28, the latter being keyed to their respective rollers. Driving gears 29 and 30, keyed to the shaft 31, serve to drive the various gears above described, and the shaft 31 is driven from tight and loose pulleys 32 and 33. When it is desired to bring the rollers 9, 10 and 11, 12 close together, the drive may be directly between the gears 27 and 28 without the assistance of the intermediate gears 25 and 26, in which case the plate 24 would have to be moved to the left as viewed in Fig. 1 in order to remove its gears from contact.

An adjusting screw 34 is rotatably mounted as at 35 to the top plate 5 for the purpose of positioning it in any desired position and a similar device will of course be employed on the other side of the machine.

The faces of the rollers as shown in Fig. 2 are straight, but they may have any other desired shape corresponding to the shape of the packages, as illustrated for example in Fig. 3, where the numerals 9^a, 10^a, 11^a, 12^a, and 36^a denote corresponding parts. A flat-sided box B is shown passing between the rollers which are shaped to fit the cover C and ridges R and S on this box.

The electrical connections to the rheostat are shown in Fig. 4 and the purpose is to connect all of the heating irons to a single rheostat 20. The heating irons 17, 18, 19, and 20 are shown as coils in Fig. 4, and the rheostat is designated by numeral 20. Irons

9 and 10 receive current through a wire 35 and irons 11 and 12 through a wire 36 from the rheostat, the connection being through a single circuit 37. The currents leave 5 through connections 38 and 39 respectively. The electric cables 40 and 41 as shown in Fig. 1 may be provided with removable sockets so as to facilitate an instant disconnection.

10 In the operation of the machine, packages are suitably supplied by hand or by a feeding mechanism and fed in between the rollers so that each set of rollers will bear upon opposite sides of the package. For example, if a rectangular tin box is being fed 15 through, it will occupy a central position and rest on opposite sides of rollers 9, 10, 11, and 12 so that the tin foil with which the tin box is covered will be fused to the top 20 and bottom thereof along both sides throughout the entire length of the box as it passes between the rollers. Other kinds of packages may be likewise treated even though they comprise yieldable contents. 25 The separate sets of rollers make it possible to secure independent adjustments against the opposite sides of the packages so as to insure a secure and close contact with the rollers. The latter are heated to the proper 30 fusing temperature by the stationary heating irons within them, and this heating temperature may be above 400 to 600° F. as described in the aforesaid patent to E. J. Conley. As furthermore described in said 35 patent, the foil may be relatively thin foil, that is, foil having a thickness less than 3/1000 of an inch, such as 1/1000 of an inch. The rheostat is of such a design that close regulation of the temperature is made possible and a reduction in the current may be 40 easily and quickly made when the machine for any reason is running slowly or has been stopped.

A dry lubricant such as mica may be used 45 in the roller bearings so that none of the lubricant will work its way out onto the rollers and interfere with the fusing operations.

As many apparently widely different embodiments of this invention may be made 50 without departing from the spirit thereof, it is to be understood that we do not intend to limit ourselves to the specific embodiment thereof except as indicated in the appended claims.

55 We claim:

1. A receptacle sealing machine which comprises a linearly separated pair of roll-

ers provided with heating means; sliding blocks carrying said rollers, each block having an independent adjusting means for positioning the rollers; and a second pair of linearly separated rollers lying in substantially the same plane as the first pair and opposite thereto.

2. The invention in claim 1 wherein the 65 rollers have internal stationary electrical heaters.

3. The invention in claim 1 wherein the 70 second pair of rollers is provided with positive driving means.

4. The invention in claim 1 wherein the 75 second pair of rollers is provided with driving means and the first pair of rollers is provided with means for driving them at the same rate from the driving means for the second pair.

5. The invention in claim 1 wherein the 80 rollers are shaped to fit accurately the entire contour of the receptacle to be sealed.

6. A receptacle sealing machine comprising 85 two independent sets of rollers, stationary heating devices in the rollers, means for adjusting each set, gears mounted to rotate with the rollers, an adjustable intermediate set of gears mounted to be placed in mesh with the above mentioned gears, and a driving gear on a driving shaft for driving the gears.

7. A receptacle sealing machine comprising 90 two separate sets of rollers each set having identical axes, stationary heating devices in the rollers, independent adjusting mechanism for each set, gears mounted on the rollers, a movable plate provided with gears to mesh with the said gears, and a driving gear on a driving shaft to drive all of said gears.

8. A receptacle sealing machine comprising 95 a plurality of individual rollers divided into sets lying on either side of a median plane through the receptacle being sealed, and means for heating the rollers.

9. A receptacle sealing machine comprising 100 a plurality of individual rollers divided into sets lying on either side of a median plane through the receptacle, means for heating the rollers, gears mounted to rotate with the rollers, and means for driving the gears.

110 In testimony that we claim the foregoing, we have hereunto set our hands this 23rd day of May, 1922.

EDWIN J. CONLEY.
EDWARD J. WHALEN.
